UNITED STATES PATENT OFFICE

FRANCES M. GRAU, OF WASHINGTON, NEBRASKA

LEG AND ANKLE PROTECTOR

Application filed October 6, 1928. Serial No. 310,764.

This invention includes an article of wearing apparel, and relates to a covering for the legs and ankles as a protection in cold or inclement weather, and has for its objects to provide coverings or protectors which may be readily and conveniently placed upon or removed from the person.

I am aware that ankle covers and leggings have heretofore been used for the above 10 named purposes, but they have been secured to the legs, ankles or feet by means of numerous buttons or buckles and are not convenient or practical in use, and are of expensive construction.

15 The present invention includes such a construction that buttons, buckles, straps or the like may be avoided, and such a construction that either thin or heavy fabrics may be used and, in either instance, wrinkling 20 will be prevented, and the holders for securing the protectors upon the person will be entirely concealed from view.

A specific object of the invention is to provide protectors of such construction that 25 they may be manufactured at a very limited expense and will present a smooth surface when worn upon the person.

With the foregoing objects in view and others to be mentioned hereinafter the invention presents a new and useful construction, combination and arrangement of parts 30 as described herein and claimed, and as illustrated in the accompanying drawing, wherein,—

35 Fig. 1 is a view of the device showing the protector applied to the leg of the wearer, and illustrating its use as an article of wearing apparel for women. Fig. 2 is a view of the same showing adaptability of the protector for men. Fig. 3 is an enlarged perspective view of the protector shown in Fig. 1. Fig. 4 is an enlarged perspective view 40 illustrating the protector shown in Fig. 2. Fig. 5 is a plan view of a stabilizing spring. Fig. 6 is a transverse section through the 45 device. Fig. 7 is a plan view of a spring clasp.

Referring now to the drawing for a more 50 particular description, it should be stated that the protector is adapted for the use of

men, women and children, the only difference required being size and proportion, the protector for use of women being shown in Figs. 1 and 3 of the drawing, and the protectors for the use of men being shown 55 in Figs. 2 and 4. Figs. 5, 6, and 7 illustrate springs used in the manufacture of all the protectors.

I provide a flexible cover 8 shown in Figs. 1 and 3 of the drawing, having a length sufficient to cover the ankle and calf of the leg and to extend approximately to the knee, also having such proportions for its lower end that it will cover the upper part of the shoe 9 of the wearer, and having a sufficient 60 width so that, when worn, it will adequately cover the calf and will be disposed in overlapped relation at the posterior part of the leg.

As best shown in Fig. 6 of the drawing, 70 the cover consists of an outer fabric sheet or part 10, an inner fabric sheet or part 11 stitched at its edges to the edges of the part 10. Numeral 12 indicates a stabilizing strip or spring. It is disposed between the 75 fabric parts 10 and 11 and by means of rows of stitches 13 at the sides and ends of said spring the latter is secured midway between the opposed edges 14 of the cover.

As thus described it will be seen that the 80 spring 12 is disposed midway between the edge-portions 14 of the cover 8. Also the rows of stitches 13 form a sheath for receiving said spring 12, the rows of stitches being disposed at the ends as well as at the sides 85 of this spring.

The spring 12 is constructed of very thin steel, and it will be understood that it operates to prevent wrinkling of the cover 8.

Numeral 15 indicates a curved steel spring 90 best shown in Fig. 7 of the drawing. I have shown rows of stitches 16 to form sheaths transversely of the cover 8 for receiving springs 15, said rows of stitches being of such arrangement that they are disposed at 95 the ends as well as at the sides of said springs 15 so that the latter are confined in their sheaths.

The curved springs 15 are constructed of extremely attenuated spring steel and their 100

weight will not be appreciable, and the weight of the springs 15 and spring 12 will not cause any inconvenience in the use of the covers.

It will be noted that, as best shown in Fig. 7, the end-portions 17 of the springs 15, are disposed in overlapped relation, and for operation, when placing the cover upon the leg and ankle, the legging or cover is manually spread to open position, and, on account of the action of the springs 15, the terminal portions 14 of the cover will move to overlapped positions and will fit snugly upon the leg and ankle, and, as is obvious, the cover or protector may be readily removed.

In Figs. 2 and 4 of the drawing, which illustrates the cover or protector for use of men the construction is similar to that already described. This cover or protector 29 8' is provided at its middle with a stabilizing-spring 12 held in position by rows of stitches 13, the same as already described. Also the cover consists of outer and inner sheets or parts 10 and 11 as described and 25 the same kind of attenuated, curved springs 15 are used and are secured by rows of stitches 16 as described, the only difference of the protector shown in Figs. 2 and 4 as 30 compared with the protector shown in Figs. 1 and 3 being one of proportion. The protector for use of men has a lesser length and has a sufficient width to permit the legs of the trousers 18 at their ends to be received.

It will be appreciated that the protectors 35 will be very useful. They may be quickly applied to the legs and ankles, may be readily removed and will be securely held in position while in use. They may be worn 40 by children as well as adults. They, of course, may be produced in suitable colors, and since no buttons, straps or buckles are used their appearance will not be objectionable.

45 While I have shown three curved springs 15 for each protector, a lesser or greater number may be used if desired.

It will be understood that the leg and ankle protector, described herein could be 50 used as leggings for overshoes, their lower ends being suitably attached to the overshoes (not shown) and such a construction, it is considered, would be within the scope of the invention for the reason that no changes 55 would be required so far as the leg and ankle protectors are concerned.

Since the springs are enclosed in the cover by means of the rows of stitches, any end thrust of the springs will be prevented. The 60 spring 12 will be disposed at the front of the cover to maintain the cover in a stretched condition, and since wrinkling will be prevented the spring 12 operates to maintain the springs 15 in uniformly spaced relation.

I claim as my invention,—

A leg and ankle protector, comprising a pair of fabric sheets stitched together at their marginal edge portions and providing a space between the sheets, a flat vertical spring disposed in said space and located midway between the lateral edges of the sheets and extending substantially throughout the length of the sheets, and a plurality of horizontal cross springs curved to the general configuration of the leg and ankle disposed at spaced intervals throughout the length of the vertical spring and interposed between said sheets, said horizontal springs adapted to overlap at their free ends at a point diametrically opposite the vertical spring, and lines of stitching securing said sheets together and extending along the opposite edge and end portions of said springs to provide individual pockets for the springs for maintaining the same against edgewise and longitudinal displacement between the sheets, said lines of stitching reinforcing the sheet structure and maintaining the sheets from separating.

In testimony whereof, I have affixed my signature.

FRANCES M. GRAU.
